UNITED STATES PATENT OFFICE

2,239,074

JACKET

Perkins H. Bailey, New York, N. Y., assignor to
Talon, Inc., a corporation of Pennsylvania

Application May 20, 1938, Serial No. 209,084

1 Claim. (Cl. 2—96)

My invention relates to jackets and like garments having a full length front opening.

The invention solves the problem of applying a slide fastener to a jacket or coat of sufficient length to extend substantially below the waist line. In garments of this type, if a slide fastener is applied in the conventional manner the bottom or skirt portion is so tight that it will not allow the necessary freedom of action when the wearer is exercising or in sitting position.

According to my invention, a slide fastener is employed for closing the front opening and is fastened directly to the fronts of the garment down to about the waist line and then extends into facings which are connected to the bottom portions of the garment in such a way as to allow free movement and expansion of the lower end of the jacket. In the accompanying drawing, I have shown for purposes of illustration, one embodiment which my invention may assume in practice. In this drawing:

Fig. 1 is a front view of a jacket embodying my invention;

Fig. 2 is a detail view of the lower end of the jacket showing how the garment is free to expand at that point; and

Fig. 3 is a cross-section on line 3—3 of Fig. 2. The jacket is generally of a conventional design having a right front panel 4, left front panel 5, collar 6 and sleeves 7. It may or it may not have a belt 8, as desired, but it is of sufficient length to extend substantially below the waist line to provide a skirt portion 9. The full length front opening 10 is closed by a slide fastener 11 of any well known construction having a separable bottom end fitting 12. The edges of the opposite front panels 4 and 5 are folded over to provide flaps or facings 13 which are preferably held in position by stitches 14 extending down to about the waist line and running along close to the fastener. At about the waist line the rows

of stitches 14 terminate and extend across the facing as at 15, thence downwardly along the edge as at 16. This provides free flaps or tongues 17 to which the slide fastener may be connected. 5 The skirt portion of the garment can thus expand because the inturned edges of the facings 13 are free to move away from the inner face of the garment. This provides a bellows effect so as to give free-movement in sitting positions and at the same time, it gives a neat closed appearance to the garment when the wearer is standing.

While I have shown and described in this application one embodiment which my invention may assume in practice, it will be understood that this embodiment is merely for the purposes of illustration and various other forms may be devised within the scope of my invention as set forth in the appended claim.

What I claim as my invention is:

A garment of the class described of sufficient length to extend below the waist line and having a full length front opening, a slide fastener extending substantially throughout the length of the opening, and means connecting the fastener to opposite sides of the garment, the attachment of the fastener being close to the opening from the top down to the approximate waist line in order to hold the garment snug around the chest of the wearer, the connecting means at the lower end including a facing of substantial width on opposite sides of the garment turned under the edge of the material bordering the opening and being free at its inturned edge from the front of the garment, and a flap carried by said inturned edges of said facing and extending back to and in substantial alignment with the front opening, said fastener below the approximate waist line being attached only to said flap in line with said front opening.

PERKINS H. BAILEY.
